APPARATUS FOR SWEATING OUT
FUSIBLE METALSWilliam F. Eppensteiner, Rahway, N. J., assignor
to The American Metal Company, Limited, New
York, N. Y., a corporation of New York

Application December 6, 1934, Serial No. 756,271

9 Claims. (Cl. 266—33)

My present invention relates to apparatus for reclaiming more readily fusible metals from those of lesser fusibility by the application of heat. More specifically it relates to the recovery of such fusible metals by the sweating out thereof from their union with metals of lesser fusibility by the application of superheated steam. The invention is applicable to the salvaging of various metals from articles or defective structures containing them, such, for example: solder from automobile radiators, lead from electric cable coatings, Babbitt metal from bearings, tin from tin-plate on cans and the like, and in numerous other instances where a more fusible metal or alloy is to be separated from a less fusible metal or alloy.

The method and means heretofore commonly employed to bring about such separation of metals of the class described has been to place the material to be treated in an oven or retort and subject it to the heat of combustion applied either externally or internally thereof, the more fusible metal or alloy falling into a receiver or tray beneath, while the less fusible metal or alloy is pushed out or otherwise removed from the container. Various means have already been proposed for agitating the metals being treated to promote separation of the fused from the non-fused metal to increase the yield of the metal to be recovered.

The objects of the present invention are to provide an apparatus whereby the treatment of metal articles or structures from which metals are to be reclaimed can be carried out on a large scale and in a continuous manner, wherein the percentage yield of the recovered metals will be substantially greater than has been heretofore possible of accomplishment, and wherein the objectionable effects of oxidation on the recovered metals will be practically eliminated.

The foregoing and other objects of the invention not specifically enumerated are accomplished by subjecting the metals or articles from which the desired metals are to be salvaged to a heat treatment in a non-oxidizing atmosphere at elevated temperature, preferably by superheated steam contained in a chamber while said articles are being conveyed therethrough, agitating said articles to free the more readily fusible metal therefrom and collecting said fused metal in reservoirs from which it may be intermittently tapped. Preferably the articles being treated are subjected to a preliminary heating by the spent steam after leaving the treatment chamber proper, moving in a direction counter to said

articles to remove therefrom contaminating and oxidizing influences and also raise their temperature before they are subjected to the sweating process. The invention will be better understood from the detailed description which follows, when 5 preheating and heating chambers of the apparatus.

Figures 1 and 1a are fractional front elevations of an apparatus embodying my invention.

Fig. 2 is a transverse section taken substantially along the plane of the line 2—2 of Fig. 1.

Fig. 3 is an enlarged fractional longitudinal section through the adjacent portions of the preheating and heating chambers of the apparatus.

Fig. 4 is an enlarged fractional longitudinal section through the remainder of the heating chamber and showing the bosh pit into which the articles, after being treated, are discharged.

Fig. 5 is a section taken substantially along the plane of the line 5—5 of Fig. 4 and showing the connection between the heating chamber and a superheater.

Fig. 6 is a section taken substantially along the plane of the line 6—6 of Fig. 4.

Fig. 7 is a transverse section taken substantially along the plane of the line 7—7 of Fig. 4 and showing in elevation the conveyor for carrying away articles from the bosh pit, and a baling press for acting upon such articles.

In the accompanying drawings which illustrate a practicable embodiment of my invention, the apparatus may be said to consist of a charging conveyor A, feed conveyors B and C, a trommel D, a bosh pit E, a discharge conveyor F and a baling press G. The conveyor C, the trommel D and the bosh pit E, are preferably enclosed in a steel casing or box H to provide a substantially air-tight closure for the unit comprising said parts. The steel box H may conveniently be formed with double, spaced apart walls h and $2h$, suitably reinforced, the space between said walls being filled with a heat insulating material $3h$, such as diatomaceous earth. The steel box H, it will be understood, will have a configuration 45 adapted to enclose the aforementioned parts of the unit, suitable provision being made to take care of expansion and contraction of the plates in view of the considerable difference in temperatures between the interior of the casing and the outside atmosphere under operating conditions. The entire unit may be supported upon a suitable foundation of concrete or the like J, while the housings A' and B' enclosing the conveyors A and B, respectively, may be supported upon a frame- 55

work or foundation J' constructed of steel, reinforced concrete or the like material.

The charging conveyor A may be of any standard link belt, apron type construction, and may be driven by means (not shown) around the sprocket wheels *a* and *2a*, and *b* and *2b*, respectively. The charging end of the conveyor A extends beyond the housing A', and to preclude the free admission of air into the housing during the charging operations there is provided within the housing A' a pair of longitudinally spaced apart flat doors *3a* and *4a*, so arranged that one of the doors will be closed, as shown at *3a*, when the other will be open. The charging conveyor is inclined upwardly and is adapted to discharge the articles carried thereby to the feed conveyor B over a downwardly sloping apron *5a* leading from the discharge end of the conveyor A to the charging end of the conveyor B.

Between the housings A' and B' and extending upwardly therefrom at the place of union is a vent stack K of a height and diameter to provide the necessary draft to draw the heating medium (superheated steam) through the casing H from the discharge end thereof and through the housing B' from the discharge end thereof.

The feed conveyor B extends through the housing B' which constitutes a preheating chamber for the articles to be acted upon. Said conveyor B, like the conveyor A, may be of any standard link belt, apron type, and as shown in Fig. 2, consists of carrying plates or pans *2b* supported by rollers *3b* adapted to ride over tracks *4b*. To prevent the articles being carried by said conveyor from jamming within the chamber and from contacting the walls of the housing, there are mounted within the casing above the conveyor, skirt boards *5b* of any desired construction and material. The housing B' through which the conveyor B extends is formed with spaced openings *6b* in its side walls, the function for which will be presently made apparent.

The conveyor C upon which the articles to be treated are sweated, extends through the heating or sweating chamber of the device and may be of any preferred construction, and as herein shown is of the chain, grate type and consists of pivotally connected links *c* which support angle iron crossbars *2c* which may be conveniently welded to the links with the angles of the bars pointing upwardly, as best shown in Figs. 3, 4 and 5. The links of the conveyor carry rollers *3c* and the link chains are trained over sprocket wheels *4c* and *5c*, while the rollers *3c* travel over tracks *6c* suitably supported by the inner wall of the casing H. Above the conveyor C and suitably supported by the inner wall of the casing are skirt boards *7c* somewhat analogous to the skirt boards *5b* in the preheating chamber, for preventing the jamming between the chain and the casing of the articles while being conveyed through said chamber. It is intended that the conveyor C in its travel through the heating or sweating chamber be practically non-agitating.

For transferring the articles from the conveyor B to the conveyor C I provide an inclined chute L.

Disposed between the upper and lower components of the conveyor C are a plurality of V-shaped troughs M formed of steel or other suitable material and connected together along their top edges by angle irons *m*. These troughs M extend completely across the width of the casing and cover the entire area beneath the upper component of the conveyor. The troughs are all mounted to tilt slightly transversely of the hous-

ing, and at their lower ends are fitted with discharge or tap-off tubes *2m* which extend through the wall of the casing, and said tap-off tubes, in turn, are fitted at their ends with rotatable elbow or L-tubes *3m* which act as valves which are adapted when turned downwardly to draw off the molten metal from the troughs into suitable receiving receptacles or molds *4m*. At the opposite or higher ends of each of the troughs M the casing is formed with an opening *5m* for facilitating the cleaning out of the troughs or the removal of dross and dirt from the top of the molten metal. Each of these openings is fitted with a door *6m* suitably hinged in any conventional manner to open and close and provide a tightly closed joint. The ends of the troughs adjacent the doors *6m* are provided with inclined closures *7m*, while at the opposite ends the troughs are provided with baffle plates *8m* which extend over the entrance of the tap-off tubes *2m* so that all metal to be tapped off must flow underneath the baffle, thereby precluding the passage of dross and dirt from the troughs unless they be tapped practically dry.

The trommel D into which the articles being treated are discharged from the conveyor C may be of any desired or preferred construction, and as herein shown, consists of a cylindrical screen *d* suitably reinforced by longitudinally extending T-beams *2d* and by circumferentially disposed encircling hoops *3d* and by end hoops or rings *4d* and *5d*, respectively. The end rings each carries a machined steel tire *6d* or *7d*, respectively, which ride upon trunnion rollers *8d* mounted upon suitable pedestals or bearings. The tire *6d* is formed around its periphery with equally spaced recesses or sockets *9d*, within which engage the teeth on a driving wheel *10d* driven by a suitable electric motor (not shown). The axis of the trommel is tilted slightly toward the discharge end in order to keep the articles being treated moving in that direction. Beneath the trommel and extending throughout its length and across the width of the casing are a plurality of V-shaped troughs M', which, in construction, disposition and function, are quite similar to the troughs M hereinbefore described.

For facilitating the transfer of the material from the discharge end of the conveyor C to the trommel I provide a transfer apron N, and for taking the thrust of the articles when falling upon the entrance end of the trommel I prefer to reinforce the same with a conical plate *11d*. I also prefer to provide a chamber below the discharge end of the conveyor C and to provide in said chamber an inclined plate O extending from the floor of said chamber to the top of the apron N. The function for said plate O will be presently made apparent.

The bosh pit E located at the discharge end of the trommel is adapted to receive the articles discharged therefrom. The bosh pit may be suitably constructed of concrete or the like and has suitable water connections *e* for filling the pit and sewer connections *2e* for draining the pit. Within said bosh pit there are mounted suitable bearing supports *f* provided with tracks *2f* and bearings (not shown) for rollers *3f* and *4f* for suitably guiding the lower end of the conveyor within the pit and providing a receiving station for the articles discharged from the trommel. For guiding the discharge of the articles from the trommel to the conveyor F an apron *3e* supported by the wall of the bosh pit may be provided. Where the apparatus is constructed in twin units so that a single bosh pit may serve

for both, a second apron 4e may be provided, as shown in Fig. 4. For excluding access of the air to the trommel through the bosh pit, the connections between the casing enclosing the 5 trommel and the bosh pit are all water sealed, for example, by the depending plate 5h (Fig. 4) and the depending plates 6h (Fig. 7).

The discharge conveyor F at its upper end leads to a chute P for transferring the articles 10 after having been passed through the sweating process to the baling press G. This baling press may be of any desired or preferred construction, and as herein shown is of the screw spindle type, which may be motor operated and consists of 15 a plunger g operable by power applying means 2g to compress a mass of material within the top of a casing or cylinder 3g to bale the same, after which said baled mass may be ejected from the cylinder by an air operated plunger or the like 20 4g into an open top freight car or the like Q.

Superheated steam for heating the chamber for sweating operations may be supplied by any 25 type of superheater R having the requisite capacity. The steam may be charged to the superheater from an ordinary steam supply line S and discharged from the superheater through the pipe T, it being understood that the superheater will be equipped with the necessary indicating 30 pyrometers and other appurtenances for maintaining a constant temperature. From the pipe T the superheated steam may be conducted to the casing H at two points, (1) through the pipe T' to the discharge pipes t within the chamber around the trommel; and (2) through the pipe 35 T'' into the heating chamber containing the conveyor C at or near the discharge end of said chamber. The pipes t and T'' may be suitably formed with holes through which the steam may enter the respective chambers.

40 It will be understood that the invention is adapted for use for treating various types of devices for reclaiming more readily fusible metals from the less fusible metals with which they are associated. Specifically the present device has 45 been designed for reclaiming solder from automobile radiators, and in describing the operation of the device such radiators will be considered as the articles acted upon.

Operation.—The radiators U are manually 50 placed in position on the feed conveyor A, either together with their frames or with their frames removed. Depending upon the capacity of the device, the radiators may be charged two wide and two or three high on the conveyor with their 55 hose connections pointing downwardly. In the course of this feeding and charging operation it will be understood that one of the flat doors 3a or 4a will always be closed so as to exclude an inrush of air or a discharge of steam from the 60 charging compartment of the casing H. From the conveyor A the radiators are fed over the apron 5a onto the conveyor B within what is termed the preheating chamber of the device. In this preheater the superheated steam from the 65 trommel chamber and the heating chamber enclosing the conveyor C will slowly pass on its way to the stack K out to the atmosphere, and in said passage air will be admitted through the openings 6b which will serve to lower the temperature 70 of the steam as it approaches the charging end of the preheating chamber, and conversely, said steam will serve to progressively heat the radiators as they approach the heating chamber proper. The superheated steam is charged to 75 the heating and trommel chambers at slightly

above atmospheric pressure so as to exclude the entrance of atmospheric air from said sweating chambers. The draft created by the stack K will usually be sufficient to cause a normal flow of the steam from the sweating chambers through 5 the preheating chamber and also draw cooling air through the openings 6b and cause it to pass in the same general direction as the steam, which is contrary to the direction of feed of the radiators. It will thus be appreciated that as the 10 steam is being progressively cooled, the radiators are being progressively heated and freed from adhering moisture and other volatile matter.

From the conveyor B in the preheating chamber the radiators will be discharged over the 15 apron L onto the conveyor C into the heating or sweating zone. Here the action of the superheated steam upon the radiators as they travel along causes the solder to be sweated out and fall between the angle bars c down into the 20 V-shaped troughs M underneath. At the end of the conveyor C the radiators will be fed over the apron N into the trommel D, where, by the tumbling action thereof, practically all the remaining free or uncombined solder is removed 25 from the radiators and caught in the V-shaped troughs M'. The traveling conveyor C in the steam-heated chamber provides for the separation of the molten metal under conditions of practically no agitation, while the trommel D 30 provides separation under conditions of violent agitation. Separate pans being provided for the collection of the fusible metal under each of these conveyors, it will be appreciated that two types of metal are produced and thus kept separate. The metal collected in the troughs M under the non-agitating conveyor C is more pure than that collected in the troughs under the 35 trommel D. More specifically, in treating automobile radiators, the solder collected in the 40 troughs M under the conveyor C is found to be somewhat richer in tin than that collected in the troughs under the trommel.

From the trommel the radiators are discharged into the water filled bosh pit for cooling and are 45 therein received upon the discharge conveyor F and carried to the baling press G where they are baled and discharged into the flat car Q. Where the radiators have been charged to the device together with their frames, these frames will be 50 manually removed from the conveyor F as they come up out of the bosh pit so as not to interfere with the baling of the substantially solder-free brass. The solder is tapped at intervals from the V-shaped troughs through the L-tubes 3m 55 into the molds 4m. Just prior, however, to the tapping operation the dross is preferably removed from the various troughs through the clean-out doors 6m. As the device is primarily intended to be continuously operating, such 60 tappings may be carried out, say once in every eight hour shift or oftener, if found necessary.

The entire apparatus may be shut down for a thorough clean out once every ten days or two weeks, and in this connection it may be stated 65 that the only places whereat trouble has been experienced in the practical operation of the device are at the discharge end of the conveyor C and at the entrance to the trommel. To reduce these troubles to a minimum I have provided at the discharge end of the conveyor C the chutes or aprons N and O. The trouble aforementioned is primarily caused by the fact that a large part of the radiators when arriving 70 at the discharge end of the conveyor C are in 75

ribbon form and very often these ribbons are carried beyond this discharge point between the angle bars *c* forming the grate, thus dropping underneath the conveyor. The apron *O* serves 5 to deflect this material down into the chamber at the foot of said plate, which chamber is provided with the clean out door *o*. The plate *O* has also been made removable so as to permit access to the trommel proper through said door. 10 Experience has taught that at times the material carried beyond the discharge point, as explained above, accumulates and builds up against the underside of the conveyor, causing a jam which necessitates shutting down the entire unit until 15 said material can be cleaned out. It has also been found that these ribbons occasionally build up in the intake end of the trommel and gradually build back to the grate conveyor, causing a jam at said point. To indicate to the operators 20 that either of these plug ups are taking place, ammeters have been installed on the operating platform to indicate the current consumption of the two main drive motors. By this means the operators can check the current consumption of 25 the motors, and when these show a constant rise above the normal operating range, the operators know that trouble is developing and can immediately shut down the unit for clean out, which operation can usually be done in a short time 30 without cooling off the entire equipment.

As previously pointed out, the clean out door *o* will serve for cleaning out any accumulations below the discharge end of the conveyor *C*. For freeing the front end of the trommel, a door *V* 35 has been provided in the roof of the casing *H* over the discharge end of the conveyor *C*. A clean out door *X* may also be provided in the casing *H* at the feed end of the conveyor *C* to remove from beneath the apron *L* any accumulations 40 which may take place therat.

For removing solder from radiators, experience has taught that the best operating temperatures are as follows: in the trommel sweating chamber, from 800 to 875° F., and at about six feet inside 45 the intake end of the sweater, from 750 to 775° F. The temperature of the heating or sweating chamber within which the grate conveyor *C* moves, is regulated by controlling a high temperature steam valve *Y* in the line leading from 50 the superheater to the conveyor chamber, while the temperature to the sweater over all is regulated primarily by the quantity of saturated steam admitted to the superheater. This can always be controlled by setting the automatic temperature 55 regulators at whatever degree of heat is required.

While I have shown and described an apparatus which was primarily designed for sweating out solder from radiators, it will be appreciated and understood that the invention is not to be construed as limited solely for this purpose, since 60 it will be apparent to those skilled in the art that changes in construction, proportions and mechanical details may be varied within the scope of engineering skill without departing from the spirit of my invention.

What I claim is:

1. An apparatus for treating metals comprising a heating chamber, a preheating chamber in open communication with the heating chamber, conveyor means movable through the chambers, means for charging superheated steam to the heating chamber, and means adjacent the article charging end of the preheating chamber for drawing the superheated steam through the heating and preheating chambers, the preheating 75

chamber having air inlets for the admission of air to lower the temperature of the superheated steam as it is drawn through the preheating chamber.

2. An apparatus for separating out more fusible 5 metals from less fusible metals with which they are united, comprising a chamber adapted to contain a non-oxidizing high temperature atmosphere, a traveling conveyor and a trommel at the discharge end of the conveyor adapted to receive metals treated by the conveyor, both the conveyor and the trommel being movable within the chamber, and separate means below the conveyor and below the trommel for collecting the molten metal separated from the less fusible metals by the high temperature atmosphere while traveling through the chamber. 15

3. An apparatus according to claim 2, wherein the ends of the trommel are open and the axis of the trommel is tilted slightly toward the discharge end thereof. 20

4. An apparatus for treating metals comprising a chamber adapted to contain a high-temperature, non-oxidizing atmosphere, conveyor means having openings therethrough movable 25 in the chamber, substantially V-shape troughs below the conveyor means and transversely disposed with respect thereto for receiving molten metal, said troughs being connected together at their tops to provide continuous receiving means 30 for the molten metal, and means leading from said troughs to the outside of the chamber for tapping off the molten metal from the troughs. 35

5. An apparatus for treating metals comprising a chamber adapted to contain a high temperature, non-oxidizing atmosphere, conveyor means having openings therethrough movable 40 in the chamber, substantially V-shape troughs below the conveyor means and transversely disposed with respect thereto and declined toward 45 one end for receiving molten metal, means on the outside of the chamber leading from the lower ends of the troughs for tapping off the molten metal from the troughs, and a baffle in each trough extending down therein below the draw-off tube at the draw-off end to prevent dross from being drawn off. 50

6. An apparatus for treating metals comprising a chamber, conveyor means having openings therethrough movable in the chamber, substantially V-shape troughs disposed transversely of and below the conveyor means, means at the outside of the chamber leading from one end of the troughs for tapping off molten metal from the troughs and a door in the chamber at the opposite end of each trough for skimming off the dross from the molten metal and for cleaning out the trough. 55

7. An apparatus for treating metals comprising a chamber, a conveyor grate and a trommel at the discharge end of the conveyor grate movable within the chamber, an inclined slide for transferring articles from the discharge end of the conveyor grate to the trommel, and an oppositely inclined deflector slide extending from the first slide rearwardly below the conveyor. 60

8. An apparatus for treating metals comprising a chamber, a conveyor grate and a trommel at the discharge end of the conveyor grate movable 70 within the chamber, an inclined slide for transferring articles from the discharge end of the conveyor grate to the trommel, an oppositely inclined deflector slide extending from the first slide rearwardly below the conveyor, and a clean 75

out door in the chamber near the bottom of the deflector slide.

5. An apparatus for separating out more fusible metals from less fusible metals with which they are united, comprising a chamber adapted to contain a non-oxidizing, high temperature atmosphere, a practically non-agitating conveyor and a violently agitating conveyor arranged in tandem within the chamber, the violently agi-

tating conveyor being adapted to receive the metals being treated from the practically non-agitating conveyor, and separate means below each conveyor for collecting the molten metal separated from the less fusible metal by the high temperature atmosphere while traveling through the chamber. 5
